UNITED STATES PATENT OFFICE.

HARRY B. ROUSE, OF CHICAGO, ILLINOIS, ASSIGNOR TO H. B. ROUSE & COMPANY,
OF CHICAGO, ILLINOIS, A CORPORATION OF ILLINOIS.

PRINTER'S COMPOSING STICK.

Application filed February 6, 1928. Serial No. 252,271.

My invention relates to printers' composing sticks and resides in the provision of means whereby the knee of such a stick may be given a rapid or coarse initial adjustment 5 and a subsequent and finer adjustment.

The initial adjustment is desirably accomplished by means which limits the knee to predetermined positions whose spacing is measured in picas, the stick of my invention 10 being thus capable of being used similarly to composing sticks of the prior art. After being given such an adjustment, the knee may be further moved a portion of a pica, the construction being preferably such that the subsequent 15 adjusting movements are limited to predetermined fractions of a pica. Both adjustments together may thus serve to locate the transverse branch of the knee a number of picas and a selected pica fraction from the cooperating end of the stick.

In the preferred embodiment of the invention, the knee is formed in two sections, one of these sections and the body portion of the stick having cooperating formations enabling 25 this section to be held in different predetermined positions along the stick, the other of said sections being adjustable along the stick with reference to the first, there being means for holding said knee sections together 30 when they have been placed in their selected relative positions. Intermeshing gears are also desirably employed, each of said knee sections having one of said gears thereon, one of the gears being operated to operate the other and thereby bring these sections in selected 35 relation. One of said gears is preferably in the form of a pinion and the other in the form of a rack and the pinion desirably carries an index whose outer end is receivable in any one of a number of notches which are 40 evenly spaced apart. The distance between adjacent notches is such that when the index is moved from one notch to the next, the two sections of the knee will be relatively moved only a fraction of a pica along the stick.

The invention will be more fully explained in connection with the accompanying drawing in which Fig. 1 is a plan view of a composing stick constructed in accordance with 45 the preferred embodiment of the invention, parts being broken away and other parts being shown in section; Fig. 2 is a sectional view on line 2-2 of Fig. 1; Fig. 3 is a sectional view on line 3-3 of Fig. 1; Fig. 4 is a side

view with parts shown in section; Fig. 5 is 55 a full plan view of the portion of the stick shown in Fig. 1; and Fig. 6 is a full side view of the portion shown in Fig. 4.

The composing stick illustrated has many features in common with composing sticks of the prior art. The body portion of the stick of which a part 30 is illustrated is constructed, as usual, to constitute a type receiving tray having an end wall 31 and a side wall 32. Said side wall has a number of rectangular 60 perforations 33 formed therethrough and distributed along the length of the stick, adjacent perforations being a pica apart at their centers.

The longitudinal branch of the knee is 70 formed in two sections 34, 35 which are relatively movable longitudinally of the stick and which are held in predetermined relation, as will be more fully hereinafter set forth. The transverse knee branch 36 is integrally 75 cast with the knee branch section 34. The knee branch section 35 is formed with teeth 37, adjacent teeth being spaced a pica apart, at their centers, these teeth being received in selected perforations 33 whereby the position 80 of the knee as a whole along the stick may be selected. Any position thus selected for the knee as a whole is maintained by the usual clip 37' pivoted upon the knee part 34, 36 between the sides of which clip the stick side 85 wall 32 and the knee branch section 34 are gripped when said clip is depressed to hold the knee portion 35 in fixed relation to the body portion 30. The knee branch section 35 is received in a slot 38 which is formed lengthwise in the knee branch section 34. The knee branch section 35 is itself formed at one end with a slot 39 through which a pin 40, upon the knee branch section 34, is passed to guide the knee branch section 34 in its movement along the stick and with reference to section 35 to further position the transverse knee branch 36 with reference to the end wall 31.

A leaf spring 41, anchored to the knee 100 branch section 34 presses the other end of the knee branch section 35 against the knee branch section 34, as illustrated most clearly in Fig. 1. A gear in the form of a pinion 42 is journaled in the knee branch section 34, 105 and meshes with the other gear 43 which is in the form of a rack which is provided upon the knee branch section 35. An index fin-

ger 44 is fixed upon the pinion 42 and may be grasped, as a handle, to turn the pinion when the knee branch sections 34 and 35 are to be relatively adjusted, for the purpose stated. Inasmuch as the knee branch section 35 is held in fixed position by the teeth 37 and the perforations 33, the knee branch section 34 is alone moved longitudinally of the stick when the pinion is turned. The gearing 42, 43 is speed reducing gearing, the movement of the knee branch section 34 effected by the gearing being small with respect to the movement of the finger engaged portion of the handle.

15 An arcuate scale 45 is formed with evenly spaced teeth 46 between any adjacent two of which the outer end of the index 44 may be received in order to hold the knee branch section 34 in the position to which it is adjusted by the operation of the pinion. In practice, the index may be initially set at the tooth space marked 0 upon the scale 45. The knee, as a whole, is then adjusted until the knee branch 36 coincides with the selected one of the pica scale marks shown at the left of the body portion of the stick, Fig. 1. If the distance between the parts 31 and 36 is to be further increased a fraction of a pica, the index 44 is turned counter-clockwise until the knee branch 36 is fully moved the desired pica fraction away from the part 31, the index finger being then inserted in the corresponding inter-tooth space to hold said knee branch 36 in its finally selected position. The index 44 may be formed of stiff spring steel whose point is constrained, due to the resilience of the index finger, to en-

ter any inter-tooth space with which it is placed in register.

While I prefer to form the knee branch 34, 35 in relatively movable sections, as described, the invention is not to be thus limited.

Changes may be made without departing from the invention.

Having thus described my invention, I claim:

A printer's comprising stick including the type receiving body portion thereof; a knee having a branch extending transversely of the stick and a branch extending along the stick, the branch that extends along the stick being formed in two sections, one of these sections and said stick-body portion having cooperating formations enabling this section to be held in different fixed positions along the stick, the other of said sections being adjustable along the stick with reference to the first, the first aforesaid knee branch section having a gear rack thereon; a pinion journaled upon the other of the aforesaid knee branch sections and meshing with said gear rack; a handle coupled with the pinion for turning it and terminating in an index portion; and an arcuate scale formed with evenly spaced teeth with which the pointing end of said index portion may be engaged in order to hold the knee branch section that carries the pinion in the position in which this knee branch section is placed by turning the pinion.

In witness whereof, I hereunto subscribe my name.

HARRY B. ROUSE.
